UNITED STATES PATENT OFFICE.

THOMAS CLAYTON GILBERT, EUGENE JASPER TABLER, AND JESSE TRIGG TABLER, OF ATLANTA, GEORGIA; SAID GILBERT ASSIGNOR TO LOUIS WELLHOUSE, OF ATLANTA, GEORGIA.

STAMP-AFFIXING MACHINE.

No. 904,948.

Specification of Letters Patent. Patented Nov. 24, 1908.

Application filed December 12, 1907. Serial No. 406,141.

To all whom it may concern:

Be it known that we, THOMAS CLAYTON GILBERT, EUGENE JASPER TABLER, and JESSE TRIGG TABLER, citizens of the United States, 5 residing at Atlanta, in the county of Fulton and State of Georgia, have invented certain new and useful Improvements in Stamp-Affixing Machines; and we do declare the following to be a full, clear, and exact description of the invention, such as will enable others skilled in the art to which it appertains to make and use the same.

This invention relates to improvements in stamp-affixing machines.

15 The object of the invention is to provide a machine of this character by means of which stamps may be rapidly affixed to envelopes or packages, means being provided whereby the stamps are moistened and separated before 20 being affixed.

With this object in view, the invention consists of certain novel features of construction, combination and arrangement of parts as will be described hereinafter and particularly pointed out in the appended claims.

In the accompanying drawings, Figure 1 is a side view of a stamp-affixing machine constructed in accordance with the invention, parts of the operating mechanism being 30 shown in dotted lines; Fig. 2 is a front view of the same; Fig. 3 is a detail sectional view of a portion of the supporting frame and the feeding roller, showing the manner in which the latter is turned to feed the stamps 35 forward; Fig. 4 is a detail sectional view through the feed roller on the line a—a of Fig. 3; and Fig. 5 is a detail sectional view of the plunger, the stamp-holding arms and the moistening devices carried thereby.

40 Referring more particularly to the drawings, 1 denotes a supporting frame comprising parallel side plates, 2, which are connected at their upper ends by a forwardly projecting cross bar, 3, adapted to serve as a 45 guide bracket for the stamp-affixing plunger of the machine. On the forward edges of the side plates 2, at the base of the machine, is formed a forwardly projecting table, 4, upon which the envelopes or packages rest 50 while the stamps are being affixed thereto. On the rear portion of the side plates is arranged a cover plate, 2^a, the lower end of which is in the form of a door, 2^b, adapted to

be opened for the insertion of a roll of stamps.

55 In the bracket 3 is formed a centrally disposed guide passage through which is adapted to be reciprocated a stamp-affixing plunger, 5, having on its upper end a knob or handle, 6. On the lower end of the plunger 60 is arranged a stamping head, 7, and around the plunger shaft between the bracket 3 and the knob 6, is arranged a coiled spring, 8, the tension of which is exerted to raise and normally hold the plunger in an elevated position. 65 On the inner side of the plunger shaft adjacent to the lower end, is formed a rearwardly projecting toothed rack, 9, which is adapted to be engaged with a centrally disposed spur gear wheel, 10, fixedly mounted 70 upon a transversely disposed shaft, 12, which is journaled in suitable bearings in the side plates 2 of the machine.

75 On the shaft 12 adjacent to the inner side of one of the side plates 2 is fixedly mounted a second spur gear wheel, 13, which is adapted to mesh with a gear 14, loosely mounted upon a feed roller shaft 15, which is mounted in the side plates 2, below the shaft 12. On the inner side of the gear wheel, 14, 80 is formed an annular series of ratchet teeth, 16, which are adapted to turn in the recessed end 17 of a feed roller, 18, and are adapted to engage a spring projected pawl 19, arranged in said recessed end of the roller as 85 shown, whereby when the plunger is depressed and motion imparted thereby through the rack, 9, and gear wheels, 12, 13 and 14, to said ratchet teeth, the latter will 90 turn the feed roller 18 in the proper direction for feeding the stamps forwardly.

95 Mounted on a transversely disposed shaft, 20, which is journaled in the side plates 2, is a lower feed roller, 21, between which and the upper feed roller, 18, the strip of stamps is adapted to pass. The stamps are provided 100 in strips which are wound upon a reel shaft, 22, the ends of which are removably journaled in inclined bearing slots, 23, formed in the rear edges of the opposite side plates, 105 2. The shaft 22 is normally held in operative position in the bearing slots 23, by means of retaining hooks, 24, which are pivotally mounted on the outer sides of the side plates 2, as shown. The strip of stamps when unwound, passes over a guide roller,

25, the ends of which are journaled in the side plates, 2, and from said roller the strip of stamps passes between the feeding rollers 18 and 21.

5 After leaving the feed rollers, the strip of stamps is fed over a supporting shelf, 25, and then through a severing device which is here shown in the form of shears, consisting of a lower stationary cutting blade, 26, which 10 is bolted or otherwise secured to the forward edge of the side plates, 2, and a movable blade, 27, which is pivoted at one end to the adjacent end of the stationary blade, and is adapted to co-act with the latter to sever one 15 stamp at a time from the strip. The movable blade 27 is restored to its normal position and held up by means of a leaf spring, 28, which is secured to the stationary blade, 26, adjacent to the pivoted end of the movable blade.

The movable blade of the shears is operated by means of a dog or pawl, 29, which is pivotally mounted on one side of the stamp-affixing head, 7, whereby when the plunger 25 is depressed, the projecting end of the dog will be engaged with the tip or outer end of the movable blade, 27, of the shears, thereby depressing said blade and causing the same to co-act with the lower stationary blade to 30 sever the stamp. The dog 29 is pivotally mounted on the head 7 in such a manner that when the same is engaged with the movable blade of the shear, the latter will be operated as hereinbefore described, but upon 35 the upward movement of the plunger, the dog will be rocked or tilted downwardly when brought into engagement with the shears, thus permitting the dog to pass. The dog is restored to its normal position after 40 passing the shears on the upward movement of the plunger head by means of a retracting spring, 30.

Carried by the plunger, 5, is a stamp-applying device on which are arranged combined stamp-holding and moistening devices. The applying-device is herein shown and preferably consists of a pair of spring metal arms, 32, the upper ends of which are connected by a cross bar which passes through a 50 slot in the plunger shaft, and is connected to a retracting spring, 33, arranged in a recess, 34, formed in said shaft. The extreme lower ends of the arms, 32, are curved or bent outwardly to form supporting fingers, 35, which, when the plunger is depressed, will come into engagement with the envelop and cause the arms, 32, to spread apart, the purpose of which will be hereinafter described.

Secured to the inner sides of the arms, 32, 60 are the combined stamp-holding and moistening devices which are here shown and are preferably in the form of shallow rectangular boxes, 36, formed of metal and having their upper sides closed by thin perforated covers, 37. The boxes 36 are adapt-

ed to contain sponges, or other absorbent material which is kept wet when the machine is being used. The moisture from said sponges or absorbent material will ooze or seep through the perforated covers of the 7 boxes and moisten the stamp when deposited thereon in a manner hereinafter to be described.

The arrangement of the rack, 9, on the plunger is such that on the downward movement of the plunger, the upper end of the rack will pass out of engagement with the gear, 10, at the same moment that the dog 29 engages the shears to cause the same to sever the stamp. When the rack has thus 80 become disengaged from the gear 10, the feeding operation ceases so that no stamps will be fed during the remainder of the downward movement of the plunger in the operation of severing the stamp and affixing the same to the envelop. Upon the upward movement of the plunger, when the rack engages the gear, 10, the latter and the gears driven thereby are turned backwards. This motion, however, will not be 90 imparted to the feeding roller, 18, for the reason that the ratchet teeth, 16, on the gear, 14, will play loosely over the pawl, 19, which connects the ratchet teeth with the upper feeding roller. The stamp-holding 95 arms 32 are moved downwardly by the engagement of the plunger head, 7, with the boxes, 36, as the plunger is depressed. The initial upward movement of the arms, 32, upon the retraction of the plunger is accomplished by means of the coiled spring, 33, which is connected to the cross bar at the upper ends of the arms and is arranged in the recess in the plunger shaft, as hereinbefore described.

In using the machine, it is the intention to place a stack of envelops on the table, 4, with their corners in proper position to receive the plunger and to consecutively stamp the envelops in the stack, drawing off the 110 top envelop as the stamp is affixed thereto. In operation the plunger 5 is pressed downwardly by the hand and the rack 9 engaging the gear wheel 10, transmits motion to the upper feed roller through the medium of the 115 gears 15 and 14, and the ratchet teeth and pawl as hereinbefore described, thereby feeding the strip of stamps forwardly between the shears and over the moistening devices. As the plunger descends and thus 120 feeds the stamps forwardly, the dog on the plunger head will engage the upper shear blade at the proper time to sever the stamp on the end of the strip, said stamp being deposited upon the moistening devices on 125 the holding arms, and held thereon by the plunger head, 7, which at this time is in engagement with said moistening devices. A further downward movement of the plunger forces the stamp holding arms and 130

moistening devices downwardly until the spreading fingers, 36, engage the envelop and force said arms and devices apart, thereby depositing the stamp in position upon the envelop, where it is fastened by the pressure of the plunger head, 7, thereon. The pressure of the stamp on the moistening devices by the plunger causes the moisture from the sponges therein to seep through the perforated covers of the devices, and thus moisten the stamp as it is being pushed downwardly by the plunger.

Having thus described our invention, what we claim as new and desire to secure by Letters-Patent, is:

1. In a stamp-affixing machine, a supporting frame, a stamp-affixing plunger, means actuated by the movement of the plunger to move a strip of stamps forwardly, means whereby the stamps are severed from the strip, spring stamp-carrying arms, stamp-moistening devices on said arms, and means whereby the latter are spread apart to deposit the stamp on the envelop, substantially as described.

2. In a stamp-affixing machine, a supporting frame, a spring-retracted stamp-affixing plunger slidably mounted in said frame, stamp-feeding rollers, a train of gears actuated by the movement of said plunger to operate said feeding rollers, a severing device operated by the movement of the plunger to successively sever the stamps fed forward by said feeding rollers, spring stamp-carrying arms, means whereby the strip of stamps is moistened, and spreading fingers on the lower ends of said arms whereby the latter are operated to deposit the stamp, substantially as described.

3. In a stamp-affixing machine, a supporting frame, a spring-retracted stamp-affixing plunger slidably mounted in said frame, a rack carried by said plunger, stamp-feeding rollers revolvably mounted in said frame, a train of gears operated by the rack on said plunger, means whereby said gears are operatively connected to the upper feeding roller to turn the same in one direction when the plunger is depressed, and to prevent the retrograde movement of the roller when the plunger retracts, a stamp-severing mechanism actuated by the movement of the plunger, expansible stamp-carrying arms connected to said plunger adapted to convey and deposit the severed stamps on the envelops, substantially as described.

4. In a stamp-affixing machine, a stamp-affixing plunger, a stamp-severing device actuated by said plunger, stamp-carrying arms connected to the plunger, spreading fingers on the lower end thereof, and combined holding and moistening devices on said arms, substantially as described.

5. In a stamp affixing machine, a stamp affixing plunger, a stamp-severing device ac-

tuated by the latter, spring stamp carrying arms connected to said plunger, combined holding and moistening devices carried by said spring arms and comprising boxes or receptacles adapted to contain absorbent material, and perforated covers on said boxes whereby the moisture from the material will seep through and moisten the stamp when deposited on said covers substantially as described.

6. In a stamp-affixing machine, a supporting frame, a spring retracted stamp-affixing plunger, a rack carried by said plunger, upper and lower revolvably mounted stamp feeding rollers, a train of operating gears adapted to be driven by said rack, an annular series of ratchet teeth carried by one of said gears, a spring projected pawl arranged in said upper stamp feeding roller and adapted to be engaged by said ratchet teeth, whereby the roller is turned in one direction, stamp-severing shears arranged on said frame, a pawl carried by said stamp-affixing plunger to operate said shears at the proper time for severing the stamp, and means whereby the stamps are moistened after being severed, substantially as described.

7. In a stamp-affixing machine, a supporting frame, an envelop supporting table connected thereto, a spring retracted plunger slidably mounted in said frame, a rack carried by said plunger, upper and lower stamp feeding rollers journaled in said frame, a train of driving gears operatively connected to said rack, a pawl and ratchet mechanism between one of said gears and said upper feeding roller, whereby the latter is turned in one direction upon the downward movement of the plunger and adapted to remain idle upon the upward movement of the plunger, a reel shaft revolvably mounted in said frame and having wound thereon a strip of stamps adapted to be fed forwardly and unreeled by said feeding rollers, stamp-severing shears comprising a stationary blade, a co-acting movable blade pivotally mounted on said stationary blade, a pivoted pawl carried by said plunger and adapted to operate said movable shear blade on the downward movement of the plunger, means to hold and moisten the severed stamp, and means to deposit the same on the envelop in position to be engaged and fastened by the plunger, substantially as described.

8. In a stamp-affixing machine, a supporting frame, a spring retracted plunger slidably mounted in said frame, upper and lower revolvably mounted feeding rollers, means actuated by said plunger to operate said feeding rollers, whereby the strip of stamps is fed forwardly through the machine, stamp-severing shears, means carried by the plunger to actuate said shears and to sever a stamp at the proper time, spring retracted stamp-holding arms, stamp moistening devices on

said arms adapted to catch and hold said severed stamp, and spreading fingers on the lower ends of said holding arms whereby the latter are spread apart to deposit the stamp on the envelop when said arms are forced downwardly by the plunger, substantially as described.

In testimony whereof we have hereunto

set our hands in presence of two subscribing witnesses.
